UNITED STATES PATENT OFFICE.

PHILLIP KRAKAUER, OF BROOKLYN, NEW YORK, ASSIGNOR TO KAY MANUFACTURING CO., OF BROOKLYN, NEW YORK, A CORPORATION OF NEW YORK.

SPRING CUSHION STRUCTURE.

Application filed March 7, 1924. Serial No. 697,442.

The invention relates to spring cushions and particularly to the structure of that type of cushions in which each spring is held in an individual pocket.

The various objects of my invention can best be understood from the description which follows, and from the accompanying drawings, in which,

Fig. 1 is a combined top plan view and partial horizontal section of a cushion structure embodying my invention.

Fig. 2 is a vertical section of the same taken on the line 2-2 of Fig. 1.

Fig. 3 is a perspective view of one of the strips forming the pocket as it appears in position, and Fig. 4 is a front view of the same as it appears before it has been bent and seamed into position.

Spring cushions have heretofore been made largely in units, each unit comprising a complete row of springs entirely encased and ready for insertion into a casing, each spring being contained in an individual substantially cylindrical pocket. It has been found that the structure just described is wasteful of material due to the duplication of material for covering the ends of the pockets. Other cushions have, therefore, been made with substantially square pockets for individual springs by seaming partitions to the top and bottom of a casing and thereby utilizing the casing for one or both of the ends of the pockets.

My improved structure contemplates the use of a partly open semi-cylindrical and semi-square pocket formed of short pieces of material which are usually wasted, whereby I am enabled to save considerable material and am further able to use a minimum of labor in the assembly of said structure.

An outer casing as 10 has secured thereto suitable strips as 11, substantially of the same height as the height of the completed pockets together with the seamed edges 21 and 22 thereof and of substantially less width than twice the width of the completed pocket. After the attachment to the top 14 and to the bottom 15 of said casing, of one of the edges as 21 and 22 respectively of each strip 11, the peripheral edges of said casing may be brought together and seamed as at 13 to form a closed structure, complete with springs as 12 suitably held therein. To stretch the casing 10 into its preferable rectangular prismatic form, wherein a top

14, a bottom 15, sides 16 and 17, and edges 18, are formed, reliance is preferably had upon the extension of the springs 12 into contact with said top 14 and bottom 15 after said springs have been inserted into the unseamed casing, as will be more fully described hereinafter.

I prefer to bend each of said strips 11 into a pair of walls 19 and 20 in mutually perpendicular relation, one wall as 19 being made substantially parallel to the side 17 of the cushion structure, while the other wall as 20 is made substantially parallel to the edges 18 of said structure, said strips being arranged in rows, so that the walls 19 of one row of strips are in alignment and the walls 20 of a perpendicular row are also in alignment.

The inner faces of said walls 19 and 20 cooperate with the outer faces of the corresponding walls of adjacent partitions to form the complete pocket. Before assembling the pocket structure, I prefer to mark on the inner surface of the top 14 and of the bottom 15 of the casing 10, lines substantially in the form of a series of squares indicating in which positions and at which points the partitions 11 are to be seamed.

It will be seen that each of said strips 11 is thereby formed into angular form with the edges 21 and 22 thereof turned preferably outwardly from the walls, and seamed as by means of the seams 23 and 24, to the top 14 and the bottom 15 of the casing, respectively.

Each of said partitions 11 is preferably slitted inwardly from the edges 21 and 22, a sufficient distance, as by means of the slits 40, each substantially perpendicular to the edges of said partition, to allow said partition to be bent readily into the perpendicular pocket walls 19 and 20. By reason of said slits, I am enabled to round the corners of the pocket at the juncture of the walls 19 and 20 to follow substantially the cylindrical shape of the spring 12, as will be seen from Fig. 3. This results in a considerable saving of material. Furthermore, by reason of the divergence of the edges of the slits 40 when a convex surface as 41 on the outer face of the angle at the juncture of the walls 19 and 20 is formed, I eliminate the creases and folds which would otherwise result when the partition 11 is bent at right angles to form said walls, thereby making the seaming of the edges 21 and 22 to the casing 10

as by means of the seams 23 and 24, a rapid and simple operation requiring little time and effort.

It will be seen that each of the strips 11 is positioned in the same relative position in the cushion structure so that the bend 41 thereof, as viewed in Fig. 1, is at the lower left-hand corner of each of said strips. It will also be noted that the strips 11 are entirely independent of, and are unconnected to, each other in any way, whereby a series of openings as 25 of substantial size are formed near the ends of said strips, and between adjacent strips, through which openings a suitable spring carrying tool, or the hand carrying a compressed spring, may be passed in a direction parallel either to the side 17 of the cushion structure or to the edges 18 of said structure to reach any or all of the pockets in a row. It will be obvious from the fact that no material is used at said spaces that considerable material is eliminated from the otherwise substantially square pocket without loss of the spring enclosing effect of the pocket, said pocket being stitched at the top and bottom, and said spaces being made considerably less than the diameter of a spring 12, whereby said spring cannot pass out of the pocket through said spaces. It will be understood that for the purpose of inserting the springs 12 into their respective pockets, the side 17 or one of the edges 18 of the casing 10 may be left unseamed by the stitching 13 until all of said springs have been inserted into their respective pockets.

It will also be understood that when a suitable spring carrying tool is inserted into the pockets through the spaces 25 and through the edge 17 of the cushion structure, that the row of pockets to the right of said tool, as viewed in Fig. 1 is filled by said tool, while if the tool is inserted between the rows and through the spaces 25 through the upper edge 18 (Fig. 1) that row of pockets to the left of said tool is filled. After insertion of all of the springs into the pockets has been completed, the edges of the casing 10 are brought together, and readily seamed by the stitching 13, completing the structure, and maintaining the parts in their permanent operative relation.

Only one thickness of material is provided at all parts of each pocket of my improved cushion for purposes of economy, while suitable spaces 25 are provided, for allowing the rapid insertion into the pockets of an entire row of springs at a time, as hereinbefore described. It will be seen that my improved arrangement of the pocket forming partition 11 provides a pocket in which two of the walls as 19 and 20 are formed by one partition, while the other two walls are formed by the wall 19 of one of the adjacent partitions and the wall 20 of the

other of the adjacent partitions, so that an individual pocket, substantially square in cross section having one rounded corner and having substantial openings at three of the corners is provided for each spring. It will also be seen that my improved structure is economical of material due to the use therein of short strips, usually of waste material, and also to the use of the slits 40 in the partitions.

Said partitions may be readily and rapidly seamed to the casing by means of a single line of stitching 44 beginning at one edge as 18 of the casing and running without interruption completely across the casing to the other edge, a second line of stitching 45 perpendicular to the line 44 being run from the side 17 to the side 16. It will, of course, be understood that to make the seams 23 and 24 in continuous lines of stitching as 44 and 45, it is advisable that the angular strips 11 be seamed to the top and bottom in such a manner that the edges 21 and 22 of said angles are turned outwardly as shown clearly in Fig. 3.

I do not wish to limit myself to the specific structure shown herein as various changes may be made therefrom, such as for instance, in the manner of folding the edges 21 and 22, in the stitching of said edges, in the lengths and positions of the slits 40, in the insertion of the springs into their pockets, in the degree of rounding of the corner of the pocket, and in the size of the spaces 25, without departing from the spirit of my invention.

I claim:

1. In a spring cushion structure, means for forming a series of substantially square pockets, having one round corner, and three open corners, comprising a multiplicity of short, upright, unconnected centrally bent strips arranged in rows parallel to the sides of said structure, each formed of an unbroken web of material, and having a pair of oppositely disposed slits, approximately at the middle thereof, extending inwardly from the edges thereof, a single pair of substantially perpendicular walls bent from each of said strips and forming two of the adjacent sides of each of said pockets, a substantially 90° bend at the juncture of said walls, edge portions bent outwardly from said walls between said slits, the outer face of the strip adjacent to one of said walls forming the third wall of a pocket, the outer face of the strip adjacent to the other said walls, forming the fourth wall of said pocket, the corresponding walls of the strips in any row being in substantial alignment, the bends of said strips being in corresponding positions in said structure and the open corners of said pockets being in substantial alignment, whereby a series of springs may be inserted into any row of said pockets simultaneously.

aneously, a casing enclosing said partitions, and forming the top and bottom of said pockets, and seams extending across said structure from one side to the opposite side, 5 and from one edge of said structure to the opposite edge, securing said edge portions to said casing.

2. In a spring cushion structure, a series 10 of independent wall forming elements, each of said elements comprising a strip of a continuous web of flexible material bent substantially at right angles along a vertical line of said strip for forming a single pair 15 of substantially perpendicular, continuous, vertical walls, said strips being so arranged that the bends thereof are in corresponding positions in said structure and that the corresponding walls of said strips are in substantial alignment, for forming pockets having aligned openings arranged in rows into 20 each of which a series of springs may be simultaneously inserted.

3. In a spring cushion structure, having a series of spring holding pockets therein arranged in rows, each of said pockets being closed at one of the corners thereof and open at the remaining corners thereof, a series 25 of separated wall forming elements each comprising a strip of a continuous web of flexible material independent of the remainder of said strips, and a single pair of substantially perpendicular continuous, vertical walls bent from each of said strips, said walls forming two of the walls and a closed corner of one 30 of said pockets and each of said walls forming one of the walls of an adjacent pocket, said walls being so arranged that the openings in said pockets are in substantial alignment whereby a series of springs may be inserted into any row of said pockets simultaneously. 35

4. In a spring cushion structure, a series of independent, separated, wall forming ele-

ments, each comprising a substantially rectangular strip of a continuous web of flexible material bent centrally along a vertical line 45 at right angles to provide two walls and a closed corner between said walls of a spring holding pocket, said strips being so arranged that the bends thereof are in corresponding 50 positions in said structure, that the corresponding walls of said strips are in substantial alignment, and that the openings in said pockets are in substantial alignment, one wall each of the two adjacent strips constituting the other two walls of said pocket. 55

5. In a spring cushion structure, a flexible casing including a top and a bottom, a series of rectangular flexible strips bent centrally on a vertical line at right angles to 60 provide rows of pockets open at three of the corners thereof, and continuous seams from one edge to the opposite edge of said casing seaming said strips at their upper and lower edges to said top and bottom, each angularly 65 bent strip forming two continuous adjacent upright walls and a closed corner of the enclosed pocket, and one wall each of the two adjoining strips constituting the other two walls of said pocket, said strips being so arranged in rows that the angular bends thereof are in corresponding positions and the corresponding walls in any transverse and longitudinal row are arranged in substantial alignment. 70 75

6. An upholstery cushion comprising a fabric body, L-shaped pieces of fabric having their upper and lower faces stitched to the inner surface of the top and bottom of said body, said pieces of fabric being arranged in longitudinal and transverse alignment relative to the body to form substantially rectangular cells and spring members arranged within said cells. 80
